UNITED STATES PATENT OFFICE.

JAMES F. McELROY, OF ALBANY, NEW YORK, ASSIGNOR TO CONSOLIDATED CAR-HEATING COMPANY, A CORPORATION OF WEST VIRGINIA.

STEAM-HEATING SYSTEM.

1,157,237.

Specification of Letters Patent.

Patented Oct. 19, 1915.

Application filed July 2, 1912. Serial No. 707,276.

To all whom it may concern:

Be it known that I, JAMES F. McELROY, a citizen of the United States, residing at Albany, county of Albany, State of New York, 5 have invented certain new and useful Improvements in Steam-Heating Systems, the following being a full, clear, and exact disclosure of the one form of my invention which I at present deem preferable.

10 For a detailed description of the present form of my invention, reference may be had to the following specification and to the accompanying drawing, which illustrates my invention, wherein—

15 Figure 1 shows my apparatus diagrammatically; Figs. 2 and 3 show the two different conditions of the reversing shift-valve.

20 My invention relates to a steam heating system, designed especially for car heating, which may be operated under high-pressure or low-pressure conditions as may be desired according as it is placed under control of a vapor trap or a pressure regulator, respectively.

25 It is now well known that a vapor regulator is one wherein the inlet valve between the source of steam supply and the radiator pipes is controlled by a thermostat subjected to the outflow from the radiator, the outlet end of the radiator pipe being usually open to the atmosphere, so that the pressure in the radiator is low. It is equally well known that a pressure trap is one wherein an outlet valve of the radiator is controlled by a thermostat subjected to the outflow from the radiator. In the latter case the outlet valve will be closed a large part of the time thereby retaining the steam pressure in the radiator, which is consequently under a comparatively high pressure of steam.

35 In my present arrangement I provide a valve by which the radiator may be placed under the control of either device at will, 45 the arrangement being such that the flow of steam through the radiator is reversed in direction in shifting from one condition to the other.

50 In the drawings the train-pipe or source of steam supply is shown at 1, and from this pipe the pipe 8 leads to my reversing shift valve A through an intermediate manual cut-off valve C. The valve A is operated by a handle α and the two conditions of this valve 55 are shown in Figs. 2 and 3. The vapor

conditions are shown in Fig. 2 and the pressure conditions in Fig. 3. From valve A the steam flows through the radiator pipe B to the vapor regulator or pressure trap according to the position of the valve. As appears 60 in Fig. 2, the steam entering valve A from supply pipe 8 will pass through the valve to pipe 9 and thence through pipe 12 to the radiator B (the branch pipe 13 leading to the pressure trap P being normally closed at 65 the trap as usual) and after passing through radiator B returns by pipe 11 to valve A and passes therethrough to pipe 10 leading to the vapor regulator V. The vapor regulator will control, in the usual manner, the flow 70 of entering steam in the supply pipe 8. The system will then operate as a vapor, or low-pressure system.

75 On the other hand, when valve A is turned as shown in Fig. 3, the flow of steam from supply pipe 8 will pass through the valve to the pipe 11 which was formerly the outflow pipe from the radiator B, but which now becomes the inflow pipe thereto. After passing through the radiator, the steam flows by 80 pipes 12 and 13 to the pressure trap P (the pipe 9 being blanked at valve A) and the trap P will then, in the usual manner, control the outflow end of the radiator pipe, the inflow from pipe 8 being free from the control of the vapor regulator V. The system will thus become a pressure system instead 85 of a vapor system.

90 What I claim as new and desire to secure by Letters Patent is:

95 1. The combination with a source of steam supply and a radiator, of a pipe connection between the steam supply and both terminals of the radiator, a thermostatic regulator controlling the pipe connection, a pressure trap in communication with one terminal of said radiator, and means in said pipe connection whereby the steam may be caused to flow through the radiator in one direction to the thermostat of the regulator, or through the radiator in the opposite direction to the trap, and excluded from the radiator.

100 2. The combination with a source of steam supply, and a radiator, of a thermostatic vapor regulator interposed between the steam supply and the radiator, means connecting the regulator with one terminal of the radiator, a pressure trap connected with the other terminal of the radiator, and 105 110

means whereby steam may be selectively caused to flow to the radiator in either direction, and the outflow of the radiator likewise caused to flow either to the trap or to the thermostat of the regulator, according to the direction of inflow of the steam into the radiator.

3. The combination with a source of steam supply, and a radiator, of a thermostatic vapor regulator interposed between the steam supply and the radiator, means connecting the regulator with one terminal of the radiator, a pressure trap connected with the other terminal of the radiator, and a manually operated valve provided with means for selectively causing the steam to flow to the radiator in either direction, and to cause the outflow of the radiator to flow either to the trap or to the thermostat of the regulator according to the direction of inflow of the steam into the radiator.

4. The combination with a radiator and a source of steam supply, of a pipe connection between the steam supply and one terminal of the radiator, a branch connection between the pipe and the other terminal of the radiator, a thermostatic vapor regulator connected with said branch and interposed between the steam supply and the radiator, said reg-

ulator being in communication with said branch connection, a pressure trap also connected with the last mentioned terminal of the radiator, and a valve provided with means whereby steam may be selectively caused to flow to the radiator in either direction, and the outflow of the radiator likewise caused to flow either to the trap or to the thermostat of the radiator, according to the direction of inflow of the steam into the radiator.

5. In a steam heating system, a radiator, a steam supply therefor, a thermostatic vapor regulator interposed between the steam supply and the radiator, a pressure trap in connection with the radiator, and means whereby the steam is caused to flow through the radiator in one direction and to return to the regulator, or caused to flow through the radiator in the opposite direction to the trap and to be excluded from the regulator.

In witness whereof I have hereunto set my hand before two subscribing witnesses, this twenty-ninth day of June, 1912.

JAMES F. McELROY.
